US0D1045284S

(12) **United States Design Patent** (10) **Patent No.:** **US D1,045,284 S**
(45) **Date of Patent:** **** Oct. 1, 2024**

(54) **BLOWER**

(71) Applicant: **Positec Power Tools (Suzhou) Co., Ltd.**, Suzhou (CN)

(72) Inventors: **Andrea Cestonaro**, Vicenza (IT); **Yanan Liu**, Suzhou (CN); **Paolo Andriolo**, Suzhou (CN)

(73) Assignee: **POSITEC POWER TOOLS (SUZHOU) CO., LTD.**, Suzhou (CN)

(**) Term: **15 Years**

(21) Appl. No.: **29/771,016**

(22) Filed: **Feb. 18, 2021**

(30) **Foreign Application Priority Data**

Aug. 18, 2020 (CN) 202030472405.1

(51) **LOC (14) Cl.** **15-05**

(52) **U.S. Cl.**

USPC **D32/15; D15/12**

(57) **CLAIM**

The ornamental design for a blower, as shown and described.

DESCRIPTION

FIG. 1 is a perspective view of a blower showing our new design.

FIG. 2 is a front view thereof.

FIG. 3 is a back view thereof.

FIG. 4 is an enlarged right-side view thereof.

FIG. 5 is an enlarged left-side view thereof.

FIG. 6 is a top view thereof.

FIG. 7 is a bottom view thereof; and,

FIG. 8 is another perspective view showing the blower with the battery attached.

The broken lines shown in the figures are for the purpose of illustrating portions of the blower and form no part of the claimed design. The broken lines showing the battery in FIG. 8 are for the purpose of illustrating environmental structure and form no part of the claimed design.

1 Claim, 8 Drawing Sheets
